MULTITRAY SERVING RECEPTACLE

John M. Black, Chicago, Ill., assignor to Superior Plastics Inc., Chicago, Ill., a corporation of Illinois

Application September 22, 1951, Serial No. 16,720

Term of patent 14 years

(Cl. D44—14)

To all whom it may concern:

Be it known that I, John M. Black, a citizen of the United States, residing at Chicago, in the county of Cook and State of Illinois, have invented a new, original, and ornamental Design for a Multitray Serving Receptacle, of which the following is a specification, reference being had to the accompanying drawing, forming part thereof.

Fig. 1 is a top plan view of a multitray serving receptacle, showing my new design; and

Fig. 2 is a side elevational view thereof.

I claim.

The ornamental design for a multitray serving receptacle, substantially as shown.

JOHN M. BLACK.
